UNITED STATES PATENT OFFICE.

JOHN P. BRADY, OF BALTIMORE, MARYLAND.

FOLDABLE METALLIC CASE.

No. 806,458.

Specification of Letters Patent.

Patented Dec. 5, 1905.

Application filed August 18, 1905. Serial No. 274,674.

To all whom it may concern:

Be it known that I, JOHN P. BRADY, a citizen of the United States, residing at Baltimore, in the State of Maryland, have invented certain 5 new and useful Improvements in Foldable Metallic Cases, of which the following is a specification.

This invention relates to metallic cases or boxes for burial purposes.

One object of the invention is to provide an improved metal case to be placed in the grave for the reception of the casket containing the body and to construct said cases so that they may be folded for convenience in storage and 15 shipping.

The invention is illustrated in the accompanying drawings, in which—

Figure 1 illustrates a perspective view of the case ready for use. Fig. 2 illustrates the case 20 in the folded condition. Fig. 3 is a vertical cross-section of the case. Fig. 4 is a vertical longitudinal section of the case with the cover removed. Fig. 5 is a vertical longitudinal section of the folded case and cover. Fig. 6 25 is a vertical cross-section of the same. Fig. 7 is a sectional view of the case and cover inclosing a casket and containing a cement filling. Fig. 8 is a detail sectional view of the roll-hinge joint, and Fig. 9 is a perspective 30 detail of one of the supporting-legs on which the casket rests.

In the drawings, 1 designates the bottom receptacle of the case, which is provided with vertical side walls 2 and end walls 3. The 35 upper edges of the side walls of the bottom receptacle are curled over to form a stationary coil 4, and the end walls 3 are also provided with a curled-over upper edge also to form a stationary coil 5 at each end. The 40 end coils 5, as clearly seen in Figs. 3 and 4, are in a plane slightly below that of the side wall coils. The bottom of the receptacle is also provided with longitudinal ribs 6, which extend upwardly on the inside and serve to 45 strengthen said bottom in a lengthwise direction. This bottom receptacle, including the ribs and coils in the present instance, is formed from a single plate; but it is obvious that it may be formed from a series of plates.

Each of the movable side walls 7 is provided 50 along its bottom edge with a fold 8, which is formed by bending the metal backward, and from said back bend the said edge is curled, so as to form a tube-like coil 9, which takes 55 around the stationary coil 4 on the stationary

side wall of the bottom. These side walls are also formed, preferably, from a single plate and are provided with horizontal inwardly-extending ribs 10 for the purpose of stiffening and strengthening the wall. The upper 60 edges of the side walls are turned inwardly and downwardly to form a stiff channel structure 11 at said edge for the cover to rest upon. Vertically-extending tapered plates 12 are riveted to the side wall, and these plates extend 65 from the channel structure, where they are narrowest, to the coil 9 at the bottom edge of the side wall. These tapered plates not only serve to strengthen the wall in a vertical direction, but they also serve to guide the case 70 when lowered into the case, so as to prevent it from striking on the horizontal ribs 10 and the coil 9.

The construction of the movable end walls 75 13 is exactly a duplicate of that of the side walls, except that the tubular coil 14, which curls around the stationary coil 5, has position in a lower plane than the coil on the side walls, and the guide-plates 15 are slightly longer than those on the side walls. 80

The cover 16 may have any desired panel or curved formation in its top plate, but the sides 17 and ends 18 turn down, so as to take over the channel structure 11 of the side walls when the latter are in the vertical position. 85

An opening may be provided in the cover for the reception of the end of a tube 19, through which cement may be poured, so as to fill the case around the casket after the grave is filled. This concrete filling, however, 90 may be placed in the case around the casket before the cover is placed thereon and prior to the filling of the grave, the object being to provide a filling that will set and harden around the casket, so that the latter will be 95 embedded in concrete and form a waterproof monolithic mass.

Suitable supports 20 are placed in the bottom of the case, so as to slightly elevate the casket from the ribs on said bottom. These 100 supports are provided with slots 21 for the ribs 6 to enter.

By reference to Figs. 5 and 6 it will be readily seen how the case is folded. The end walls are first turned inwardly, so that their 105 channel edges will lie flat on the bottom ribs. One side wall is then turned in, so as to lie on top of the end walls and the other side wall. The cover will then fit down on top of the folded side walls. 110

Having thus described my invention, what I claim as new, and desire to secure by Letters Patent, is—

1. In a foldable metallic case the combination with the bottom having upwardly-projecting side and end walls of different heights, and movable walls pivotally connected to the stationary walls of the bottom whereby the movable walls may be folded one upon the other over the bottom, and a cover.
2. In a foldable metallic case the combination with the bottom having stationary side walls provided with a curled upper edge and end walls also having curled upper edges which are in a plane below the curled edges of the side walls, and movable walls whose lower edges are also curled and engaged with

the coils on the stationary side and end walls whereby the movable walls may be folded down over the bottom.

3. In a foldable metallic case the combination with the bottom whose walls are provided with curls along its edges, of movable walls also having curls along their lower edges which engage the curls on the walls of the bottom and said movable walls also having guide-plates extending in a direction at right angles to the curled edges.

In testimony whereof I affix my signature in presence of two witnesses.

JOHN P. BRADY.
